United States Patent Office

Des. 232,425
Patented Aug. 20, 1974

232,425

WORKBOAT

John E. Marriner, 4019 Pine Ave.,
Long Beach, Calif. 90807

Filed Sept. 28, 1972, Ser. No. 292,952

Term of patent 14 years

Int. Cl. D15—04
U.S. Cl. D12—66

FIG.1

FIG.3

FIG. 1 is a perspective view of a workboat showing my new design;

FIG. 2 is a bow view of said workboat;

FIG. 3 is a stern of said workboat;

FIG. 4 is a side elevational view of said workboat; and

FIG. 5 is a top plan view of said workboat.

I claim:

The ornamental design for a workboat, substantially as shown and described.
